UNITED STATES PATENT OFFICE.

WILLIAM H. AMBUHL, OF PHILADELPHIA, PENNSYLVANIA.

DENTAL IMPLEMENT.

Application filed September 9, 1920. Serial No. 409,044.

To all whom it may concern:

Be it known that I, WILLIAM H. AMBUHL, a citizen of the Republic of Switzerland, residing in Philadelphia, Pennsylvania, have 5 invented Dental Implements, of which the following is a specification.

This invention relates to that class of dental apparatus particularly designed for holding the human mouth in an open position 10 with the jaws distended or separated more or less widely to permit of operations on the teeth, jaws, etc.; one object of said invention being to provide a device which shall at all times tend to hold the mouth open 15 and jaws distended and which may be adjusted at will either to allow the patient to close the mouth or to prevent this action.

A further object of the invention is to provide an implement of the class noted 20 which shall act to expose the teeth of both jaws while keeping the lips, cheeks, tongue, etc. away from the same, so as to avoid the necessity for the use of rubber dam, fabric or cotton pads, etc., the invention contem- 25 plating a device which may be utilized to hold or support cotton or fabric rolls or pads in such positions as to protect the tender parts of the mouth as well as to absorb saliva so as to maintain the parts operated on in 30 a dry condition.

Another object of my invention is to provide a device of the class described which shall include pad- or roll-holding members of such design and so associated with the 35 other parts of the device, that they shall be caused to follow and conform to the shape of the oral cavity as the jaws are opened or closed, instead of remaining at all times parallel with each other under these conditions.

These objects and other advantageous ends I attain as hereinafter set forth, reference being had to the accompanying drawings, in which,

45 Figs. 1 and 2 are front elevations illustrating my implement with its mouth-engaging members in their separated and adjacent positions respectively; and

50 Figs. 3 and 4 are side elevations corresponding respectively to the showing of Figs. 1 and 2.

In the above drawings 1 and 2 represent two metal bars pivotally connected by a pin 55 3, which if desired, may be outwardly extended and returned upon itself as indicated at 4, to provide a handle or operating member. In the present instance I have illustrated the bars 1 and 2 as engaged at approximately their middle points with their upwardly extending ends connected by a coil spring 4 tending to draw them together so as to lessen the angle between them. Two other bars 5 and 6, curved on substantially 65 circular arcs and pivoted together by a pin 7, have their free ends respectively pivoted to the free or lower ends of the bars 2 and 1 respectively.

The pivot 3 which connects the bars 1 and 2, serves also to connect to them a holder 8 having a passage for the reception of the suitably formed end of an upper pad carrier 9, while the pivot pin 7 which connects the lower bars 5 and 6, similarly serves to support a second holder 10 for the reception of a second or lower pad carrier 11 and this pivot, like the pivot 3 is suitably formed, as by being bent upon itself, to provide a second operating handle 12. The pad carriers or mouth-engaging members 9 and 11 may be of any desired or suitable construction and consist in this case of relatively stiff nickelized or silvered frames or open plates having such form and outline as to be suited for supporting cotton pads for engagement with and in confirmation to the forms of the soft parts of the mouth such as the tongue, hard palate, cheeks, etc.

It is especially to be noted that in accordance with my invention, if it be assumed that the upper or spring connected ends of the arms 1 and 2 lie in or adjacent a vertical plane in front of an observer, then the lower ends of said bars are bent so as to extend at an acute angle toward the rear of said plane. The lower arms 5 and 6 which are pivoted to the ends of these rearwardly bent arms 1 and 2, are curved forwardly and then brought to substantial parallelism in front of the plane of the upper parts of the arms 1 and 2 to the point where they are connected by the pivot 7.

The upper ends of said arms 1 and 2 are

preferably provided with openings 14 for the reception of the ends of a straight and relatively rigid bar or rod 15, whereby after they have been separated to a definite extent, their attached parts may be retained in the given positions by inserting the parallel ends of said bar in said openings as indicated in Fig. 2.

With the above described arrangement of 10 parts, forcing the members 3 and 7 together causes the various bars to move on their respective pivots so as to diminish the distance between the pad carriers 9 and 11 and approach positions in which their bodies are 15 substantially parallel (Figs. 2 and 4). Said carriers may now be introduced into the mouth and as the jaws are separated it is noted that the peculiar formation of the two pairs of bars 1-2 and 5-6 causes the planes of 20 the pad carriers to be increasingly inclined to each other so that they follow or conform to the general shape or disposition of the jaws and their associated members or tissues instead of remaining substantially parallel 25 or maintaining a constant angular relation.

It is to be noted that while for convenience I have referred to the elements 9 and 11 as pad carriers, it is obvious that regardless of whether or not they are utilized to support 30 pads or are employed as shown, their principal function is to serve to directly engage or act upon such parts as the tongue and roof of the mouth or if desired, certain of the teeth so as to hold the jaws separated and 35 permit free access of an operator to the teeth, etc.

I claim:

1. The combination in a dental implement of two bars pivoted together adjacent their 40 middle portions; a mouth-engaging member carried by said bars adjacent their point of connection; two other bars each pivoted to one of said first bars and also pivoted together; with a second mouth-engaging member carried adjacent the point of connection of the two latter bars.

2. The combination in a dental implement of two bars pivoted together adjacent their middle portions; a mouth-engaging member 50 carried by said bars adjacent their point of connection; two other bars each pivoted to one of said first bars and also pivoted together; with a second mouth-engaging member carried adjacent the point of connection 55 of the two latter bars, said two pairs of bars being formed to cause the mouth-engaging members to lie substantially parallel when they are moved adjacent each other and to lie at an acute angle when they are moved 60 further apart.

3. The combination in a dental implement of two bars pivoted together adjacent their middle portions; a mouth engaging member carried by said bars adjacent their point of 65 connection; two other bars each pivoted to

one of said first bars and also pivoted together; a second mouth-engaging member carried adjacent the point of connection of the two latter bars; with a spring connecting the two first bars and acting thereon to tend 70 to separate the mouth-engaging members.

4. The combination in a dental implement of two bars pivoted together adjacent their middle portions; a mouth-engaging member carried by said bars adjacent their point of 75 connection; two other bars each pivoted to one of said first bars and also pivoted together; a second mouth-engaging member carried adjacent the point of connection of the two latter bars, said two pairs of bars 80 being formed to cause the mouth-engaging members to lie substantially parallel when they are moved adjacent each other and to lie at an acute angle when they are moved further apart; with a spring operative on 85 said first pair of bars to move them into positions in which the mouth-engaging members lie at an acute angle to each other.

5. The combination in a dental implement of two bars pivoted together adjacent their 90 middle portions; a mouth-engaging member carried by said bars adjacent their point of connection; two other bars each pivoted to one of said first bars and also pivoted together; a second mouth-engaging member 95 carried adjacent the point of connection of the two latter bars; with a member for locking said two pairs of bars from movement and thereby holding the mouth-engaging members immovable.

6. The combination in a dental implement of two pairs of bars; two mouth-engaging members; a pivotal member connecting one pair of bars adjacent their middle portions and also connecting one of the mouth-engaging members to said bars; a second pivotal member connecting the ends of the other pair of bars and attaching thereto the second mouth-engaging member; two other pivots respectively connecting the bars of 105 one pair with those of the other pair; and a spring acting on the bars of one pair to tend to separate the mouth-engaging members.

7. The combination in a dental implement of a pair of bars pivotally connected adjacent their middle portions and each having one end bent out of the plane approximately defined by their other ends; two other bars having a substantially circular curvature respectively pivoted to the bent ends of the 110 first pair of bars and also pivotally connected together; with mouth-engaging members connected to the two pairs of bars adjacent their points of pivotal connection respectively.

8. The combination in a dental implement of a pair of members pivoted together; a mouth-engaging member carried by said first members; a second pair of members respectively pivoted to the members of said 130

first pair and also pivoted together; with a second mouth-engaging member carried by the second pair of pivoted members.

9. The combination in a dental implement of a pair of members pivoted together; a mouth-engaging member carried by said first members; a second pair of members respectively pivoted to the members of said

first pair and also pivoted together; with a second mouth-engaging member carried by 10 the second pair of pivoted members; and a spring acting on the pivoted members tending to separate the mouth-engaging members.

WILLIAM H. AMBUHL.
